ATTORNEY

UNITED STATES PATENT OFFICE

HERBERT F. BRADY, OF WINONA, MINNESOTA

WRENCH

Application filed October 6, 1931. Serial No. 567,271.

The present invention relates to wrenches and comprehends a construction whereby the jaws thereof can be adjusted and held fixed relatively by means operable with one hand of the user, so that the wrench can be both quickly and conveniently used.

In carrying out the invention, the wrench embodies a fixed jaw and a relatively movable jaw associated with means for adjusting the same with relation to the fixed jaw, and holding it in any given position, and which means is controlled by a single operating lever arranged in juxtaposition with the handle of the wrench to be simultaneously gripped therewith.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and where-

Figure 1 is a side elevation of a wrench constructed in accordance with the present invention.

Figure 2 is a similar view with the cover plate removed and partly in section.

Figure 3 is a view similar to Figure 2 but illustrating a different position of the operating lever.

Figure 4 is a similar view illustrating how the wrench is used.

Figure 5 is a sectional view of line 5-5 of Figure 4.

Figure 6 is a fragmentary view of the forward end of the wrench handle.

Figure 7 is a detail view of the movable jaw.

Referring to the drawings in detail 10 indicates the body of the wrench which is used as a handle, and at one end of which is arranged the fixed jaw 11. The handle is recessed for a portion of its length as at 12 to receive the operating mechanism to be hereinafter described, and is further formed with a channel 13 in which the shank 14 of the movable jaw 15 operates. The recess 12 and

channel 13 are covered by a plate 16 which is secured to the handle by fastening elements 17 so that the plate can be removed as the occasion may require. Manifestly the jaw 15 is mounted for sliding movement toward and away from the fixed jaw 11, and controlled in its movements by the mechanism to be presently described.

The shank 14 of the movable jaw is provided with a longitudinal series of teeth 18 and meshing with these teeth is the segment 19 of a gear including a relatively larger segment 20. Pivoted within the handle 10 as at 21 is a lever 22 from which projects an integral pawl 23 adapted to engage the teeth 18 of the segment 20 of said gear, and thereby normally hold the movable jaw 15 fixed with relation to the handle. A coil spring 24 has one end connected with the segment 20 of the gear and its opposite end connected with the lever 22. Consequently the lever 22 is spring influenced in one direction to normally maintain the pawl 23 in engagement with the segment 20 of the gear. Pivotedly connected with the segment 19 of said gear 75 is one end of a link 25, the opposite end of which is longitudinally slotted as at 26 and receives a pin 27 carried by the lever 22. By virtue of this construction the lever controls the movements of the sliding jaw, and is also 80 operable to effect a release of said jaw for adjustment thereof.

In practice, assume that jaws 11 and 15 are in the position illustrated in Figure 2, and it is desired to adjust the movable jaw 15. For this purpose the lever 22 is moved upon its pivot 21 within the handle 10, thereby separating the pawl 23 from the segment 20 of the gear, and when the pin 27 engages the adjacent end of the slotted link 25, the latter is pulled apart to partly rotate the gear and thereby move the jaw 15 the desired distance away from the jaw 11. During this operation the spring 24 is placed under tension, and after the wrench has been placed about the nut 28 or other object to be grasped by the jaws, the lever 22 can be slightly released to allow the spring to reverse the rotation of said gear and thereby move the jaw 15 toward the jaw 11 into proper gripping rela-

tion therewith. When the lever is fully released the spring 24 moves the pawl 23 into engagement with the segment 20 of the gear and thereby holds the jaw 15 fixed with relation to the jaw 11 in its given adjusted position. By reason of the construction illustrated wherein the lever 22 is arranged to be grasped by the same hand that grasps the handle 10 of the wrench, it will be manifest 10 that the wrench can be operated in the manner just described and quickly and conveniently used with one hand. Furthermore the jaw 15 can be easily adjusted in either direction through the instrumentality of a single 15 control lever.

While it is believed that from the foregoing description the nature and advantages of the invention will be readily apparent, I desire to have it understood that I do not limit 20 myself to what is herein shown and described and that such changes may be resorted to when desired as fall within the scope of what is claimed.

What is claimed is:

- 25 1. A wrench comprising a handle, a fixed jaw thereon, a sliding jaw mounted for movement toward and away from the fixed jaw and including a toothed shank, a gear meshing with the teeth of said shank, a spring influenced lever pivoted on said handle and connected with said gear, a pawl projecting from said lever and normally engaging said gear to hold the movable jaw stationary, and to permit adjustment of said jaw through the 30 instrumentality of said spring and gear subsequent to the release of said jaw, and means controlled by said lever for adjusting the jaw in one direction during the movement of the lever to release said jaw.
- 35 2. A wrench comprising a handle, a fixed jaw thereon, a sliding jaw mounted for movement toward and away from the fixed jaw and including a toothed shank, a gear meshing with the teeth of said shank, a lever pivoted on said handle, a pawl projecting from said lever, a spring connecting the lever and gear to normally hold the pawl in engagement with the latter and to adjust the 40 movable jaw in one direction subsequent to its release and under the control of said lever, and means controlled by said lever for adjusting said jaw in an opposite direction during the movement of the lever to effect a 45 release of said pawl.
- 50 3. A wrench comprising a handle, a fixed jaw thereon, a sliding jaw mounted for movement toward and away from the fixed jaw and including a toothed shank, a gear meshing with the teeth of said shank, a lever pivoted on the handle, a pawl projecting from said lever, a spring connecting the lever and gear to normally hold the pawl engaged with the latter, and to operate the 55 gear and adjust said jaw in one direction when released from said pawl, a link having

one end pivotally connected with the gear, and a slot and pin connection between the other end of the link and said lever, whereby the jaw is adjusted in an opposite direction during the movement of the lever to effect 70 a release of said pawl.

In testimony whereof I affix my signature.
HERBERT F. BRADY.
